PIPE FLANGING MACHINE

Foscoe H. Andrus, Windsor, Conn.

Application December 10, 1935, Serial No. 53,773

7 Claims. (Cl. 153—81)

My invention relates to that class of machines which are employed to form flanges on the ends of pipes, and an object of my invention, among others, is the production of a machine of this 5 class that shall be simple in construction and particularly efficient in operation and of such size that it may be possessed by mechanics having small shops and not requiring the use of a large machine.

10 One form of a machine embodying my invention and in the construction and use of which the objects herein set out, as well as others, may be attained, is illustrated in the accompanying drawings in which

15 Figure 1 is an end view of my improved machine.

Figure 2 is a top view of the same.

Figure 3 is a side view.

20 Figure 4 is a view of the end opposite to that shown in Fig. 1 with the parts beyond omitted.

Figure 5 is a detail view in horizontal section on a plane denoted by the dotted line 5—5 of Fig. 1.

25 Figure 6 is a view in cross section on a plane denoted by the dotted line 6—6 of Fig. 2.

Figure 7 is an isometric perspective view of the base of the machine with attached parts.

Figure 8 is a similar view of the tool feeding member.

30 Figure 9 is another similar view of the tool feeding slide.

Figure 10 is a like view of the tool supporting shaft.

35 Figure 11 is a similar view showing the two supporting dies.

In the accompanying drawings the numeral 12 denotes the base of my improved machine which is preferably composed of metal with a bearing 13 rising therefrom at one end thereof. A tool sup-

40 porting shaft 14 is rotatably mounted in said bearing, a crank handle 15 being loosely mounted on the outer end of the shaft. A ratchet 16 is secured to the shaft and a two-toothed pawl 17 is pivotally mounted on the handle for engage-

45 ment with the teeth of said ratchet. A spring 18 may be engaged with either side of the handle 15 to effect engagement of either of the pawls with the teeth of the ratchet wheel so that feeding action of the pawl will be obtained by movement

50 of the handle in either direction only. A flanging tool is secured to the end of the shaft opposite the ratchet, such tool comprising a head 19 and a flanging roller 20, the roller preferably being tapered or of frusto-conical shape.

55 A tool feeding slide 21 is mounted for sliding

movement on a slideway 22 comprising a shoulder formed on one side of the bearing 13, as shown in Fig. 7 of the drawings. This slide has a downturned lip 23 to receive one end of a spring 24, the opposite end of said spring being seated in a recess 25 in the side of the bearing 13. A feeding handle 26 is pivotally mounted in a grip handle 27 secured to and projecting from the upper side of the bearing 13. A pin 28 projects from the handle 26 through a hole 29 in the 10 slide 21.

A tool feeding member 30 is loosely mounted upon the shaft 14 adjacent the head 19, this feeding member being in the form of a disk with a stud 31 engaging an actuating lug 32 projecting from the slide 21, and as shown in Fig. 9. The projecting forward end of the bearing 13 has feed cams 33 formed on diametrically opposite sides thereof to receive cam lugs 34 projecting from diametrically opposite sides of one face of the 20 disk 30 comprising the tool feeding member.

Holding and forming dies 35—36 are held by pins 37 projecting upwardly from the base to position said dies in proximity to the flanging roller 20. The lower die 35 preferably has 25 notches 38 for engagement with the pins 37 and the upper die preferably has holes 39 through which said pins extend. The adjacent edges of the dies are recessed to receive a pipe 40 the end of which is to be flanged, and as shown in 30 Fig. 5 of the drawings. A yoke 41 is pivotally attached to the base so that it may be swung upwardly over the dies or downwardly therefrom, as shown in Fig. 7 of the drawings.

A clamp screw 42 is threaded through the upper part of the yoke to engage the upper die 36 to force the dies together and securely clamp the pipe 40 therebetween.

In the operation of the machine a pipe being secured in place as shown in Fig. 5, the handle 15 is turned to rotate the shaft 14 and thereby the flanging tool. The pawl and ratchet 17 and 16 respectively will permit a step-by-step movement of the shaft if desired by rocking the handle in opposite directions, or the spring 18 may be so 45 engaged with the handle on one edge as to enable the shaft to be turned continuously in either direction as may be desired. The other hand of the operator being placed upon the grip handle 27 which affords a support the fingers are 50 gripped under the feed handle 26 and the latter being drawn toward the handle 21, the slide 21 will be moved to effect rotation of the feeding member 30 whereby the engagement between the feed cams and the cam lugs 34 will cause the 55

shaft 14 to be moved lengthwise in its bearing against the tension of the spring 43, thereby effecting engagement of the roller of the tool feeding member within the hole in the pipe 40 and the rotation of the shaft will effect the formation of a flange on the end of the pipe or tube, as will be readily understood by an examination of the drawings.

I claim:

- 5 1. A flanging machine including a rotatably mounted flanging tool, means for supporting a pipe adjacent said tool, a shaft to support said tool, a bearing for said shaft, a cam projecting from the end of said bearing, a tool feeding disk loosely supported on said shaft, a cam lug projecting from the face of said disk to operatively engage said lug on the end of said bearing, and means for effecting relative movement between said cams to cause feeding movement of said member.
- 10 2. A flanging machine including a bearing, a feed shaft rotatably mounted in said bearing, means for rotating said shaft, means for supporting a pipe adjacent said tool, a tool feed member mounted on said shaft, a cam lug projecting from said member, a cam formed on said bearing, said cams being operatively engageable, a grip handle projecting from said bearing, a feed handle underlying said grip handle and pivotally movable with respect thereto, and an operative connection between said feed handle and said member to effect engagement of said cams to cause feeding movement of said member.
- 15 3. A flanging machine including a bearing, a shaft rotatably mounted in said bearing, a flanging tool supported by said shaft, a cam lug formed in the end of said bearing by means of a notch cut across the end of the bearing, means for supporting a pipe adjacent to said tool, a tool feeding member mounted on said shaft, a cam lug projecting from said member into said notch, and means for effecting relative movement between said cams to cause feeding movement of said member.
- 20 4. A flanging machine including a rotatably mounted flanging tool, means for supporting a

5 pipe adjacent said tool, a tool feeding member operatively connected with said tool for feeding it, a cam lug projecting from said member, a cam operatively engageable with said lug, a feeding slide, an operative connection between one of said cams and said slide to effect relative movement thereof to said feed tool, a grip handle rigidly supported, and a feed handle pivotally mounted for hand gripping action in connection with said feed handle and operatively engaged with said slide for operating it.

10 6. A flanging machine including a rotatably mounted flanging tool, means for supporting a pipe adjacent said tool, a rotatably mounted feeding member operatively connected with said tool for feeding it, a cam lug projecting from said member, a cam operatively engageable with said lug, a slide to effect rotation of said member to feed said tool, a grip handle rigidly supported, and a feed handle pivotally mounted for hand gripping action in connection with said grip handle and operatively engaged with said slide for operating it.

15 7. A flanging machine including a rotatably mounted flanging tool, means for supporting a pipe adjacent said tool, a tool feeding member rotatably mounted and operatively connected with said tool for feeding it, a cam lug projecting from said member, a cam rigidly mounted in the path of movement of said cam lug, a stud projecting from said feeding member, a slide engageable with said stud for rotating said member, a rigidly supported grip handle, and a pivotally mounted feed handle operatively engaged with said slide for operating it.

20 8. A flanging machine including a bearing, a cam formed by cutting a notch across the end of said bearing, a shaft rotatably mounted in said bearing, a feeding member mounted on said shaft and having a cam lug engageable in said notch, a slide, an operative connection between said slide and feeding member for rotation of the latter, a rigidly mounted grip handle, a pivotally mounted feed handle, and a loose connection between said feed handle and slide for operating the latter.
